PUTTER HEAD

Glenn S. Benson, 705 N. Studebaker St.,
Mishawaka, Ind. 46544

Filed Jan. 24, 1975, Ser. No. 543,828

Term of patent 14 years

Int. Cl. D21—02

U.S. Cl. D34—5 GH

FIG. 2

FIG. 3

FIG. 1

FIG. 5

FIG. 4

FIG. 6

FIG. 1 is a perspective view of a putter head embodying my new design;

FIG. 2 is a top view thereof;

FIG. 3 is an end elevational view, the opposite end being a mirror image thereof;

FIG. 4 is a rear elevational view thereof;

FIG. 5 is a bottom view thereof; and

FIG. 6 is a perspective view of a putter head having a transparent insert located between the supporting prongs and the upper surface of the putter head.

The characteristic feature of my design resides in the bifurcated support portion shown.

I claim:

The ornamental design for a putter head, as shown and described.
